SPRAY COATING MEANS

John W. Baur, Glenview, Ill., assignor to Binks Manufacturing Company, Chicago, Ill., a corporation of Delaware

Application November 16, 1951, Serial No. 256,697

2 Claims. (Cl. 299—140.1)

The present invention relates to spraying devices for spraying coating materials, especially such materials as are non-premixable for coating.

There are some coating materials or substances, such as an enamel, or like type of coating material, which when sprayed or applied, has or needs a rapid curing, and it has been found that it may be effected, as by way of example, by the use of a substance generally known as a catalyst, or the like, which acts rapidly and helps a rapid and efficient coating.

The present invention relates to a coating means or spraying device for spraying a coating material, for example such as an enamel type of coating material, or the like, as referred to above, and more particularly the means for projecting with or in such spray of coating material, the curing or like material, such as a catalyst as mentioned above, whereby the two mix or become associated or unite and react together during the spraying action or process so as to be in proper condition for coating or effecting a coating of the surface being or to be coated.

The present invention may be regarded as an improvement on the invention disclosed in the co-pending application of I. O. Johansson, Ser. No. 226,257, filed May 14, 1951, on Spray Coating Means And Method, now forfeited.

Other objects, advantages, capabilities, features, and the like are comprehended by the invention as will later appear, or as are inherently possessed by the invention.

Referring briefly to the drawings:

Fig. 1 is a part vertical sectional view and part elevational view of a spray gun employing or embodying the invention;

Fig. 2 is a part top view partly in section and partly in elevation of a part of a spray gun and of the associated improvement of the present invention;

Fig. 3 is a top plan view of the same; and

Fig. 4 is a fragmentary side view of a part of the improvement.

Referring now more in detail to the drawings, the embodiment selected to illustrate the invention is shown as comprising a spray gun 10 having a body portion 11, a head portion 12, a nozzle portion 13 connected to the head portion 12 by a suitable coupling means or the like 14, and a handle portion 15.

On the body portion 11 is pivotally mounted by way of suitable pivot means 16 a hand operated control means or trigger 17 or the like. The handle 15 preferably has an air entry passage 18 leading to a valved chamber 19 having a valve 20 for controlling the passage of air to the forward part or chamber portion 21 of the chamber 19 and which part 21 has a passage or passages 22, 23, leading to an air passage or chamber 24 leading to a passage or chamber 25, and a further passage 26 which in turn leads to the air chamber or passage 27 provided in the upper part of the body 11, as shown in Fig. 1.

The valve 20 is normally held closed by a spring 28 and this valve has a valve stem 29 slidable in the forward

2

part or portion of the chamber portion 21 and the forward part of such valve stem 29 being in operative engagement with a contact piece 30 carried by the hand operated trigger 17, when pulled back by the hand of the operator moves the rod 29 and opens the valve 20 to permit passage of air under pressure to pass by way of the passages 21, 22, 23, 24, 25, 26 to the passage or chamber 27.

The air then passes from the air passage or chamber 27 to a passage or chamber 31 provided in a connecting piece or coupling member 32 between the body portion 11 and the head portion 12 of the gun 10. This passage or chamber 31 leads to a chamber 33 provided in the head portion 12.

Within the nozzle portion 13 and in the forward portion of the head portion 12 is located a material and air passage member 34 having a forward contacting member or portion 35 seated against the nozzle portion, 13, and a rearward contacting member or portion 36 with a portion or part 37 of the head portion 12. The head portion 12 has a material inlet part or portion 38 having a material passage 39 leading to a material chamber or passage 40 provided in the material and air passage member 34 above referred to, this passage 40 leading to a tapered forward portion or part 41 having a material projecting nozzle part or tip 42 extending in a central opening 43 provided in the front 44 of the nozzle part or portion 13, and the projecting of the coating material through said nozzle part 42 being controlled by a tapered valve part 45 carried at the forward end portion of a valve stem 46 extending rearwardly in the material chamber 40 and in the gun body portion 11 rearwardly of the hand trigger member 17, and also carrying a sleeve-like member 47 slidably in the gun body 11 as shown in Fig. 1, the sleeve-like member 47 having a head 48 at the rear of the hand lever or trigger member 17 to be contacted by and moved rearwardly when the hand trigger member or means 17 is pulled back by the user's or operator's hand so as to likewise move the valve stem 46 rearwardly and hence the valve part 45 to cause it to open and to cause the coating material in the chamber 40 to be projected out as a liquid stream 49. (See Fig. 2.)

The member 34 has an intermediate portion 50 making sealing contact with nozzle portion 13 at its forward portion and with the head portion 12 at its rear portion, and has or is provided with air passages 51, 52, leading from the air chamber 33 by way of ducts 53, 54, respectively, and air ducts 51 leading to air chamber 55 provided in the nozzle portion 13, and air ducts 52 leading to the air chamber 56 in the front portion of the nozzle portion 13. The nozzle portion 13 also has air passages 59 (see Fig. 2) leading from the air chamber 55 to side ports or jet orifices 57, 58, for the projecting of side air jets or streams 107, 106 for acting on the central or projected stream or streams 49 of material projected from the nozzle or tip 42. Thus, from the chamber 55 lead air passages 59 (see Fig. 2) for supplying the air to the side orifices 57, 58 (see Fig. 2). The ducts or air passages 52 lead to the chamber 56 which chamber has air projecting orifices 60, 60, 61, 61, and also an annular opening 62, for projecting air around or against the liquid stream 49 projected from the material nozzle 42. The air jets or streams 107, 106, projected from the side or horn ports 57, 58, and all the air projected from the orifices 60, 61, and also the air projected from the annular orifice 62 will unite as shown in Fig. 2 to engage and enshroud, so to speak, the main material or liquid stream 49.

The means for projecting or supplying the curing or substance, such as a catalyst or the like, and forming,

in the main, the subject matter of the present invention, is shown in particular in Figs. 2 and 3, and comprises a body portion 63 detachably supported by or in a sort of saddle like member or the like 64 having an extension or connecting part 65 carried by or suitably attached to or is even an integral part of the spray gun, especially the head portion or part 12 thereof, and this part or portion 63 has connected to it at its forward portion a chambered member 66 as by suitable holding or securing means, such as screw threads 67, and also has connected to it 10 or at its rear portion a chambered member 68 as by suitable holding or securing means, such as screw threads 69.

The member 66 has a chamber 70 for holding the curing material under pressure, and this chamber 70 has an inlet 71 where the curing material is supplied by way 15 of a connection or fitting 72 to which may be suitably connected a suitable supply duct (not shown) for the curing material. At the forward end of the member 66 and forwardly of the chamber 70 is a valve controlled port 73 controlled by a valve 74 which has an elongated stem 75 which slidably extends through the chamber 70, the body part 63 which latter carries a sort of sealing means 76 for the stem 75, and thence along and through a chamber 77 provided in the chamber 68, and through the rear end wall 78 of the chamber 68, where the stem passes freely through an arm 79 fixed to the trigger arm 17, and the rear end of the stem 75 has a threaded portion 80 where are adjustably carried and set stops or the like 81, 82, so that when the hand lever or trigger means 17 and attached parts 79 are moved back the arm 79 will move to contact the stop or stops 81, 82, to move the valve stem 75 rearwardly and to cause the valve 73-74 to open and permit flow of the curing substance from the chamber 70.

In the chamber 77 is provided a spring 83 which is normally in compressed condition between the rear end 78 of the chamber member 68, and a thrust flange or the like 84 provided on the movable valve stem 75, whereby the spring 83 will normally hold the valve 74 closed, and return the valve 74 to closed position after release of pressure on the hand trigger 17 and return of the latter with the arm 79, stops 81, 82, valve stem 75, disc 84, and valve 74, under the influence of the spring 83.

At the forward end of the member 66 is provided a chambered part 85 in which is provided a chamber 86 in communication with the valve port 73, and this chamber 86 has a lateral opening in which is provided a nozzle member 87 having a passage 88 communicating with chamber 86 and for projecting the curing fluid in a stream or the like 89 toward and into the stream of coating material from the orifice 43 and air mixed with it from the ports 60, 61, 62 and from the side ports 57, 58 to mix therewith and to be carried therewith and to effect the curing action by the time the mixture or the like reaches the surface to be coated. The nozzle part 87 may be secured in place by suitable threads or the like 90. The body 63 of the projector may be held in place with the holding part 64-65 by any suitable securing or holding means 91.

In operation, when the hand trigger 17 is pulled back it first presses on the valve stem 29 to move it and the valve 20 to open the latter and hence permit a flow of air under pressure by way of the passages and ports as follows: entry passage 18, chamber 19 via opened port of valve 20, to chamber portion 21 and thence via ports 22 to chamber 24 and then via passages 25, 26 to chamber 27 and thence through passage 31 to chamber 33 and to both sets of air ducts and passages 53, 54 and thence via the ducts or passages 59, 59, in side horns 13, 13, and thence out through the side ports 57, 57, 58, 58 to project air jets or streams 106, 106, 107, 107 toward and to and into the air and material being projected out the front part of the nozzle portion 13, and at the same time the air is also passing from the chamber 33 via the air duct or chamber 54, 54 thence via the passages 52, 52, to the

chamber 56, and thence through the orifices 61, 61, 60, 60, 62 provided in the front wall of the chamber 56 for projecting streams of air about and around the material stream 49 issuing from the central port 43 and to be engaged by and mingled with or joined with the streams 106, 106, 107, 107 projected from the side ports 57, 57, 58, 58, at about the same time but preferably in retarded time the further movement of the hand trigger 17 causes the part in contact piece 30 to then engage and move back from the head 48 carried by the sleeve 47 which will cause a movement of the valve stem 46 to cause the material valve 45 to open the port or opening 43 to allow the coating material to pass from the chamber 40 and be projected through the port 43 into a liquid stream 49 where it is engaged by the air streams from the orifices 62, 60, 60, 61, 61, to act with and mix or unite with such air streams, and to be impacted by the side streams 106, 106, 107, 103 from the side orifices 57, 57, 58, 58; and at about the same time movement of the hand trigger 17 will cause the attached part or arm 79 to move the stops 81, 82 on the valve stem 75 with the thrust flange 84 against the spring 83 and cause an opening of the valve 74 to permit flow of the curing fluid from the chamber 70 via the valve port 73 and thence to and through the nozzle passage 88 to be projected in a stream 89 to engage with and be engaged by the combined or combining streams of material from the nozzle 13 and to so unite with or be so associated with said projected and mixing material and air to mix or become so associated therewith as to effect the desired curing action on the moving coating material so that as it arrives at the surface to be coated by it will be in such cured condition as properly and efficiently effect its coating action and result. As the curing spray is projected from its nozzle 87 it will be caused to take a curved path as shown at 89 in Fig. 2 of the drawings so that the curing fluid will move with and in generally the same direction of the coating material 49 and the engaging air therewith, so that the curing effect will take place during the transit of the combining sprays.

While I have disclosed a form of means for supplying the curing fluid for the coating material as disclosed, I do not want to be limited to the particular form of means illustrated and described.

Having thus disclosed the invention, I claim:

1. In a spray coating apparatus of the character described, a body, a primary nozzle carried by said body having a passage to project a stream of coating material, a pair of auxiliary air nozzles carried by said body on opposite sides of said primary nozzle and having passages to direct streams of air against and in the general direction of movement of said stream of coating material, and a second nozzle connected to said body having a passage to direct a stream of curing material against said stream of coating material transversely thereof to unite therewith, the projected axes of said passages converging outwardly toward and merging at a common point, trigger means carried by said body for controlling the initiation of flow of said stream of coating material, and separate means connected to said trigger means for simultaneously controlling the initiation of flow of said stream of curing material with said coating material.

2. In a spray coating apparatus of the character described, a body, a primary nozzle carried by said body having a passage to project a stream of coating material, a valve stem positioned in said nozzle for controlling the flow of coating material from said primary nozzle, a pair of auxiliary air nozzles carried by said body on opposite sides of said primary nozzle and having passages to direct streams of air against and in the general direction of movement of said stream of coating material, a second nozzle connected to said body having a passage to direct a stream of curing material against said stream of coating material transversely thereof to unite therewith, the projected axes of said passage converging outwardly toward

and merging at a common point, a valve stem for controlling the flow of curing material from said second nozzle, a trigger pivotally mounted on said body, means connecting said trigger to the valve stem of the primary nozzle, and separate means connecting said trigger to the valve stem of the second nozzle to actuate both of said valve stems simultaneously when said trigger is moved. 5
